[57] **ABSTRACT**

The method of removal of smoke particularly in confined areas by spraying an aqueous solution of a surfactant into the smoke.

1 Claim, 1 Drawing Figure

PATENTED JUN 10 1975

11

METHOD OF ERASING SMOKE

This invention relates to a novel and improved method of erasing smoke and more specifically smoke produced by a fire.

When a fire breaks out in a building, large quantities of smoke is produced which not only hampers escape of occupants but also obstructs fire fighting and rescue activities. Therefore, it is an important and essential that smoke be erased or removed from the area of the fire. Although a large-scaled smoke exhausting device is sometimes used, it must be brought to the area of the fire provided that it is not too late.

Therefore, an object of this invention is to provide a novel and improved method of erasing smoke easily without use of any special device.

According to this invention, an aqueous solution of a surfactant is sprayed into the smoke to settle the smoke particles.

The surfactants usable for this purpose are, for example, dialkyl sulfosuccinates, alkyl sulfates, alkyl benzenesulfonates, ricinolic ester sulfates, alkyl esters, of α -sulfofatty acid, monosodium α -phosphonofatty acid esters, dialkyl phosphates and polyoxyethylenealkyl sulfates (degree of polymerization: 2-20) as anion surfactants, and polyoxyethylenealkyl phenols (degree of polymerization: 2-20), polyoxyethylenealkyl ethers (degree of polymerization: 2-20) and tripolyoxyethylenealkyl phosphates (degree of polymerization: 2-20) as nonion surfactants.

This invention will be described in detail hereinunder with reference to the accompanying drawing and in conjunction with some examples.

2

tration of smoke was measured with respect to time by a method of extinction using a silicon blue cell and the smoke erasing rate was calculated. The smoke erasing rate in this example is given by Curve 1 of the drawing 5 with respect to the spray time.

EXAMPLE 2

The test was carried out under the same conditions as that of Example 1, except that 1% aqueous solution of the surfactant was used in place of the 0.5% solution. The smoke erasing rate was measured as shown by Curve 2 of the drawing and it was 68% after 30 seconds and 77% after 60 seconds and indicated clearly an increase in the smoke erasing effect over Example 1.

EXAMPLE 3

This test was carried out for the purpose of comparison under the same conditions as that of Example 1, except that the same amount of water was used in place of the surfactant solution. The smoke erasing rate was measured as shown by Curve 3 of the drawing. More specifically, it was 20% after 30 seconds and 36% after 60 seconds and clearly indicated the effect of surfactant in comparison with the above examples.

EXAMPLE 4-15

These tests were carried out under the same conditions as that of Example 1, except that 1% aqueous solutions of various surfactants listed in the following table were used in place of the 0.5% sodium di-2-ethylhexyl sulfosuccinate solution, and the smoke erasing rates after 30 and 60 seconds were measured in same fashion as shown in the same table.

35

EXAMPLE	SURFACTANTS	SMOKE ERASING RATE	
		30 SEC.	60 SEC.
4	Sodium di-n-hexyl sulfosuccinate	62	74
5	Sodium di-isobutyl 3-methylbutyl sulfosuccinate	65	77
6	Sodium di-1-methyl 4-ethylhexyl sulfosuccinate	68	79
7	Sodium lauryl sulfate	63	73
8	Sodium dodecyl benzenesulfonate	65	78
9	Ricinolyl benzyl sodium sulfate	63	75
10	Sodium butyl α -sulfolaurate	61	74
11	Sodium amyl α -phosphonocaprate	60	74
12	Poly-oxyethylene lauryl sodium sulfate (degree of polymerization: 6)	62	74
13	Poly-oxyethylene nonylphenol ether (degree of polymerization: 10)	63	73
14	Poly-oxyethylene lauryl ether (degree of polymerization: 6)	63	75
15	Tri-hydroxyethylene nonyl phosphate (degree of polymerization: 10)	65	78

The single drawing is a diagram representing smoke erasing rates of three examples.

EXAMPLE 1

2 kilograms of Japanese cedar wood and 2 kilograms of acrylic resin board were smoke in a furnace and the smoke produced was fed into a chamber having a volume of 8 cubic meters and provided with a spray nozzle in the center of the ceiling. 0.5% aqueous solution of sodium di-2-ethylhexyl sulfosuccinate was sprayed from the nozzle at a spray pressure of 10 kilograms/cm², a spray angle of 100 degrees and a spray amount (flow rate) of 50 liters per minute. The concen-

55 It should be noted that the method of this invention can not only erase smoke but also remove poisoning gases. This effect will be described in conjunction with the following examples.

EXAMPLE 16

500 grams of polyvinyl chloride resin board and 5 kilograms of Japanese cedar wood were smoked and the smoke was fed into the chamber of Example 1. 1% aqueous solution of sodium di-2-ethylhexyl sulfosuccinate was sprayed in the chamber and the concentration of hydrogen chloride gas was measured by gas chromatography. It was found that the concentration of

hydrogen chloride was reduced from 28,000 p.p.m. to 20 p.p.m. within three minutes.

EXAMPLE 17

One kilogram of nylon and 5 kilograms of Japanese cedar wood were smoked and the smoke was fed into the chamber of Example 1. 1% aqueous solution of sodium di-2-ethylhexyl sulfosuccinate was sprayed in the chamber and the concentrations of hydrogen cyanate and ammonia were measured by gas chromatography. It was found that the concentration of hydrogen cyanate was reduced from 1,000 p.p.m. to 15 p.p.m. and the concentration was reduced from 4,600 p.p.m. to 30 p.p.m. within three minutes respectively.

As described above, according to the method of this invention, smoke and poisonous gases produced by a fire can be easily and effectively removed. While the surfactant solution may be sprayed from the outside of the building by a chemical fire engine for example, it

is advantageous for it to be stored in the building for automatic spray from sprinklers installed on the ceilings.

I claim:

- 5 1. In the method of removing smoke in a building wherein smoke is produced by fire forming a smoke filled area, the improvement comprising the steps of forming a aqueous solution containing up to about 1% of a surfactant wherein said surfactant constitutes at least one substance selected from the group consisting of dialkyl sulfosuccinates, alkyl sulfates, alkyl benzene-sulfonates, recinolic ester sulfates, alkyl esters of α -sulfocatty acid, monosodium α -phosphonofatty acid esters, dialkyl phosphates, polyoxyethylenealkyl sulfates, 15 polyethylenealkyl phenols, polyoxyethylenealkyl ethers and tripolyoxyethylenealkyl phosphates and then spraying said solution into the smoke filled area to settle the smoke particles.
